UNITED STATES PATENT OFFICE.

HARRY Y. NORWOOD, OF ROCHESTER, NEW YORK, ASSIGNOR, BY MESNE ASSIGNMENTS, TO H. & M. AUTOMATIC REGULATOR COMPANY, OF ROCHESTER, NEW YORK, A CORPORATION OF NEW YORK.

TIME-CONTROLLED VALVE MECHANISM.

1,249,293

Specification of Letters Patent.

Patented Dec. 4, 1917.

Application filed December 11, 1911. Serial No. 665,104.

To all whom it may concern:

Be it known that I, HARRY Y. NORWOOD, of Rochester, in the county of Monroe and State of New York, have invented certain new and useful Improvements in Time-Controlled Valve Mechanisms; and I do hereby declare the following to be a full, clear, and exact description of the same, reference being had to the accompanying drawings, forming a part of this specification, and to the reference-numerals marked thereon.

The present invention relates to a time controlled valve mechanism, and it has for its object to provide means for admitting fluid to a retort or receiver for a predetermined period of time, and for automatically shutting off the supply and exhausting the fluid from the receiver automatically at the end of such period. A further object of my invention is to enable this end to be attained by means of a valve, suitably controlled by fluid pressure which is automatically regulated by a time mechanism. Another object of my invention is the provision of a novel arrangement of parts whereby a time mechanism may readily be set to permit the supply of fluid to the receiver for any desired length of time. To these and other ends the invention consists in certain improvements and combinations of parts all as will be hereinafter more fully described, the novel features being pointed out in the claims at the end of the specification.

In the drawings:

Figure 1 is a view in elevation of one embodiment of my invention, as applied to a time controlled valve mechanism for admitting steam to a vulcanizer, the steam controlling valve casing and pressure chamber appearing in section;

Fig. 2 is a view in elevation of the time mechanism and casing therefor, the cover of the latter being removed;

Fig. 3 is a vertical sectional view on the line $x-x$ of Fig. 2;

Fig. 4 is a horizontal sectional view on the line $y-y$ of Fig. 3, and

Fig. 5 is a vertical sectional view on the line $z-z$ of Fig. 3.

Similar reference numerals throughout the several figures indicate the same parts.

While the invention is susceptible of application wherever steam, or a similar fluid, is to be supplied to a receiver for a prede-

termined period, at the end of which it is automatically cut off, the present embodiment illustrates the invention in connection with a vulcanizing apparatus embodying a retort 1 from which a pipe 2 leads to the valve casing 3, the latter being connected by ports 4 and 5 to the inlet and exhaust pipes 6 and 7, respectively. The valve which is designated at 8, is arranged to be operated by a time controlled pressure actuated means, and to this end is carried by a valve rod 9, which extends upwardly within a chamber 10 and is suitably connected at the top of the chamber to a diaphragm 11, a spring 12 being afforded between said diaphragm and the valve casing whereby the valve is held upwardly in the position shown in Fig. 1, when the diaphragm chamber is relieved from pressure, as will be pointed out hereinafter.

The valve is arranged to be controlled by a suitable fluid under pressure, preferably compressed air, and to this end a pipe 13 leads from a suitable source of supply to the time controlling mechanism contained within the casing 14, from which a pipe 15 leads to the diaphragm-chamber 10.

Arranged within the casing 14 is a two-way valve, adapted in one position to connect the compressed air supply pipe with the diaphragm-chamber 10 so as to exert pressure on the diaphragm 11, and in its other position to cut off the supply of compressed air and connect the chamber 10 with the atmosphere so as to relieve the diaphragm 11 of pressure. To this end, I provide a conical valve 16 arranged within the casing 17 and held in proper operative relation thereto by means of the spring 18. The valve is provided with ports 19 and 20, the port 19 serving to connect the compressed air supply with the chamber 10 through pipes 21 and 22, respectively, and the port 20 serving to connect said chamber with the atmosphere through the pipe 23. In the position shown in Fig. 4, the compressed air supply is cut off and the chamber 10 is connected to the atmosphere through port 20, and when the valve is rotated to reverse the position of the ports, the atmospheric outlet is closed and pressure is admitted to the chamber. The pipes 22 and 23 are both connected to the chamber 10 through a cylindrical casing 24 to which they lead, and which,

in turn, is connected to the pipe 15 through a pipe 25.

The valve 16 is provided with an upwardly extending angular stem 26 by which it may be turned by a suitable key, for a purpose presently to be made clear, and fixedly mounted on said stem is a lock plate 27, provided with a notch, or cutaway portion 28, and carrying a pin 29 to which is connected the spring 30, the latter being suitably secured to a stationary part and serving to hold the valve normally in the position shown in Fig. 2, in which position the compressed air is admitted to the chamber 10, the valve 8 being thereby held downwardly to permit the exhaust of steam from the retort.

In order to enable the compressed air supply to be cut off for a predetermined period of time so as to admit steam to the retort, I provide a suitable time mechanism, designated generally at 31, and arranged to control the valve 16 in a manner that will now be described. Pivottally arranged in coöperative relation to the lock plate 27 is a detent 32 adapted to engage the notch 28 and hold the valve against the action of the spring 30. The time mechanism includes an arbor 33 on which is fixedly mounted a disk 34 carrying a projection 35 adapted to engage the detent 32 and move the latter away from engagement with the lock plate, the detent being mounted on a post 36 and held in engaging position by a spring 37. Loosely mounted on the arbor 33 is a pinion 38 forming a part of the time mechanism, and arranged between the pinion 38 and the disk 34 is a spring plate 39 by which said pinion is frictionally engaged with the disk 34 and with the arbor 33. This connection permits the arbor to be turned, so as to set the time mechanism for any desired period of time, and to this end it is provided with an angular portion 40 at its upper end arranged to be engaged by a key, and carries an indicator 41 coöperating with the indicating scale 42 on the cover of the casing.

In the operation of the mechanism, under normal conditions, the valve 16 is turned so as to admit compressed air to the upper side of the diaphragm 11, and to hold the valve 8 in position to permit the exhaust of the steam from the retort. When it is desired to close the exhaust, to supply steam to the retort, the arbor 33 of the time mechanism is turned by a key until the indicator points to the desired period of time for which steam is to be admitted. At the same time the valve 16 is turned by a suitable key

until the detent 32 engages the notch 28 of the lock-plate. In this position of the parts, the compressed air supply is cut off from the diaphragm 11, the upper portion of the diaphragm-chamber being exhausted to the atmosphere, and the valve 8 assumes the position shown in Fig. 1 under the action of the spring 12, thereby closing the exhaust from the retort and opening the inlet to permit the entrance of steam. This continues until the time mechanism brings the projection 35 into engagement with the detent 32, whereupon the lock-plate 27 is released, and the valve 16 is moved to its normal position by the spring 30. This permits the compressed air to again enter the chamber 10, whereby the valve 8 is moved to close the inlet and open the exhaust.

While I have described my invention with reference to a particular embodiment, it is to be understood that I am not limited to the exact construction and arrangement of parts herein disclosed, for I intend to cover by this application any modifications or departures as may come within the terms of the claims hereinafter.

85

I claim as my invention:

1. The combination with a heating or vulcanizing chamber and means for supplying heating fluid to it, of a valve controlling the passage of heating fluid to the heating chamber, pressure means acting independently of the pressure within the chamber for operating said valve and embodying a supplemental fluid pressure pipe, a second valve controlling the supplemental fluid pressure, a spring controlling the second valve, and a locking device acting to hold the latter valve against the action of the spring.

2. The combination with a heating or vulcanizing chamber and means for supplying heating fluid to it, of a valve movable to two positions and acting when in one position to admit heating fluid to said chamber and in its other position to relieve the pressure within said chamber, of means controlled by fluid pressure independently of the pressure within the chamber for actuating said valve and embodying a supplemental pressure pipe, a second valve controlling the supplemental pressure within the last mentioned pipe, a spring actuating the latter valve in one direction, and a locking device acting to hold the latter valve against action of the spring.

HARRY Y. NORWOOD.
